UNITED STATES PATENT OFFICE.

WILLIAM J. BERGENS, OF CHICAGO, ILLINOIS, ASSIGNOR TO THE NOVELTY PATENTS COMPANY, OF NORTH CHICAGO, ILLINOIS, A CORPORATION OF ILLINOIS.

EXTENSION CURTAIN ROD.

Application filed October 22, 1921. Serial No. 509,640.

To all whom it may concern:

Be it known that I, WILLIAM J. BERGENS, a citizen of the United States of America, and a resident of Chicago, in the county of 5 Cook and State of Illinois, have invented certain new and useful Improvements in Extension Curtain Rods, of which the following is a specification.

This invention relates to means for connecting extensible curtain rods of the spring actuated contractile type to their supporting side brackets or hangers, and has for its 10 object:—

To provide a structural formation and association of the curtain rod parts by which a strong and effective connection between the actuating spring and the end of the telescoping tubular member enclosing said spring is attained, and which in addition 15 provides a simple and effective attachment between an end of the curtain rod and an adjacent bracket or hanger.

To provide a simple and efficient structural formation of the hanger or bracket 20 adapted to provide a ready coupling means for an end of a curtain rod and a substantial attachment to the window casing, and which provides a construction more especially adapted for the support of a pair of curtain 25 rods in spaced relation for the support of a pair of over-draped window curtains, all as will hereinafter more fully appear.

In the accompanying drawing:—

Fig. 1, is a top view, with parts in section, 30 of the end portions of a pair of tubular extension curtain rods and the adjacent supporting bracket or hanger therefor.

Fig. 2 is a front elevation of the hanger or bracket with part thereof in section on line 40 2—2, Fig. 1.

Fig. 3, is a transverse section on line 3—3, Fig. 2.

Fig. 4, is a top view of an end portion of a single tubular extension curtain rod and 45 the hanger or bracket therefor.

Like reference numerals indicate like parts in the different views.

Referring to the drawing, 1 and 2 designate end portions of the respective inner and 50 outer tubular members of an extensible curtain rod formed to slide or telescope one within the other.

3 designates one of the hangers or brackets

fixedly attached to a window casing and having supporting engagement with the adjacent end of the curtain rods.

4 designates a portion of the operating coiled spring arranged centrally within the aforesaid rod members 1, 2 and having connection at its respective ends in a direct 60 manner with the respective outer ends of said members 1, 2, and in an indirect manner with the hangers or brackets 3 by counterpart anchor links of wire or rod metal and formed as follows:

5 designates a main loop portion the inner member or bar 5' of which is of a substantially straight shape and passes diametrically through orifices in the outer end of a tubular member 1 or 2, to afford a substantial 65 attachment for a longitudinally extending attaching eye 4' at an end of the spring 4, with said eye 4' in encircling engagement with the middle portion of the bar 5' as shown. The side bars 5'' of the loop 5 extend longitudinally from the aforesaid bar 5' and in the preferred construction shown in Fig. 1, are adapted to lay in longitudinal channels or insets formed in an end portion 70 of the circular wall of a tubular member 80 aforesaid. With such construction the side bars 5'' are within the circular exterior of the tubular member, so that said member is capable of slipping and fitting into the hereinafter described holding sleeve of a hanger 75 bracket 3.

6 designates an eye or loop having an oblique arrangement at the outer end of the anchor link to the longitudinal axis of the curtain rod, for the purpose hereinafter stated. 90 The loop or eye 6 and the main loop 5 are integrally formed from the rod material used in making the anchor link and in the construction shown one end of such rod material is connected to an intermediate portion 95 thereof by an eye or bend 6'.

In the construction shown in Fig. 1 the hanger 3, of a duplex type is formed of plate metal and has a base portion 7 adapted to bear against the face of a window casing and 100 formed at one end with an angularly disposed flange 8 having at its free end a plurality of spurs 9 adapted to bite into and have holding engagement in the edge of a window casing under the pulling stress of 105 the spring 4 aforesaid.

10 designates an open return bend in the plate metal of the hanger 3, extending from an end of the base portion 7 to near the mid-length of the same and adapted to form a 5 narrow receiving recess gap between the parts for the attaching flanges of a supplementary bracket hereinafter described.

11 designates the inner and primary plate metal bracket member forming an extension 10 from the return bend portion 10 and extending in an angular direction away from the same, with its outer and free end bent into an approximately parallel relation to the said return bend portion 10 and formed with the 15 hereinafter described attaching means for the curtain rods.

12 designates the outer or secondary plate metal bracket member of a counterpart angular formation to that of the primary member 11 and having at its inner end an attaching flange 13 adapted to fit in the aforesaid recess between the base portion 7 and return bend portion 10 and be permanently secured therein by rivets or other usual fastening 25 means. The free end of the outer member 12 as well as the like end of the member 11 are in the present improvement formed with curtain rod engaging means as follows:—

14 designates a tubular sleeve or socket 30 formed on the free end of a bracket member aforesaid, and extending longitudinally to receive and have a slip fit with an end of a curtain rod member 1 and 2 aforesaid.

15 designates an inwardly extending 35 hook arranged on a bracket member aforesaid, adjacent to the sleeve 14 and adapted for holding engagement with the eye 6 of the anchor link aforesaid. With the described construction of parts, as the end of 40 a tubular member 1 or 2 is inserted endwise into a sleeve 14, the obliquely arranged eye 6 of the anchor link rides along the back of the hook 15 and when past the same is adapted to move into line with and engage 45 said hook as the resilient stress of the spring 4 acts to draw the rod members 1 and 2 from out of the sleeves 14. The described engagement of the anchor link and sleeve parts can be readily disengaged when 50 required, by moving a member 1 or 2 by hand in a direction to take the eye 6 out of engagement with the hook 15, and while in such condition a quarter turn is imparted to the rod member to bring the obliquely disposed eye 6 out of line with the hook 15 and so that the spring 4 will be unimpeded 55 in its normal tendency to draw the curtain rod member out of the sleeve 14, when the operator releases the described hold on the 60 parts.

The single bracket type of hanger shown in Fig. 4 is adapted for the support of a single curtain and its rod, and is in part of a counter part construction to that of the 65 duplex hanger above described and con-

sists in an arrangement of parts as follows:—

16 designates a base portion formed with an angularly disposed flange 17 having casting 70 engaging spurs 18 at its free end as in the duplex hanger aforesaid.

19 designates a closed return bend in the plate metal of the hanger, extending the length of the base portion 16 and formed integral therewith.

20 designates an angular bracket member 75 extending from the end of the return bend portion 19 and formed at its free end with a receiving sleeve or socket 14 and hook 15 described above in connection with the duplex hanger structure.

Having thus fully described my invention, what I claim as new and desire to secure by Letters Patent, is:—

1. In a curtain rod and hanger, the combination of a pair of telescoping tubular members, a contractile spring intermediate of said members and provided with an end attaching eye, an anchor member having an outer attaching eye and an inner loop portion, an end portion of which extends diametrically through an end of a tubular member and engages the end eye of said spring, and a hanger provided with a hook for engagement with the attaching eye of the anchor member.

2. In a curtain rod and hanger, the combination of a pair of telescoping tubular members, a contractile spring intermediate of said members and provided with an end attaching eye, an anchor member having an outer attaching eye and an inner loop portion an end portion of which extends diametrically through an end of a tubular member and engages the end eye of said spring, the side portions of said loop fitting insets in the wall of the tubular member, and a hanger provided with a hook for engagement with the attaching eye of the anchor member.

3. In a curtain rod and hanger, the combination of a pair of telescoping tubular members, a contractile spring intermediate of said members, an anchor link connected to the end of a tubular member and spring and having an outer attaching eye, and a hanger provided with a bracket portion carrying a guide sleeve for an end of a tubular member aforesaid and a hook adjacent to said sleeve for engagement with the attaching eye of the anchor member.

4. In a curtain rod and hanger, the combination of a pair of telescoping tubular members, a contractile spring intermediate of said members, an anchor link connected to the end of a tubular member and spring and having an outer obliquely arranged attaching eye, and a hanger provided with a bracket portion carrying a guide sleeve for a tubular member aforesaid and a hook ad-

jacent to said sleeve for engagement with the attaching eye of the anchor member.

5. In a curtain rod and hanger, the combination of a pair of telescoping tubular members, a contractile spring intermediate of said members, an anchor link connected to the end of a tubular member and spring and having an outer attaching eye, and a hanger formed with an attaching flange 10 having casing engaging spurs, with a return bend portion and with an angular bracket portion, said bracket portion carrying a guide sleeve for a tubular member aforesaid and a hook adjacent to said sleeve for engagement with the attaching eye of the anchor member.

6. In a curtain rod and hanger, the com-

bination of a pair of telescoping tubular members, a contractile spring intermediate of said members, an anchor link connected 20 to the end of a tubular member and spring and having an outer attaching eye, and a hanger formed with an attaching flange having casing engaging spurs, with an open return bend portion forming a receiving 25 recess, an angular bracket member having at one end a flange fitting the said recess and at the other end carrying a guide sleeve for a tubular member aforesaid and a hook 30 adjacent to said sleeve for engagement with the attaching eye of the anchor member.

Signed at Chicago, Illinois, this 17th day of October, 1921.

WILLIAM J. BERGENS.
